UNITED STATES PATENT OFFICE

HARRY LYON, OF HOLBROOK, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

WELT TEMPERING MACHINE

Application filed September 21, 1927. Serial No. 221,056.

This invention relates to machines and processes for preparing welt for the inseaming operation and more particularly to a novel machine and process especially adapted for handling and properly tempering welt just prior to its being drawn through the welt guide of the inseam sewing machine, but it will be understood from the following description that the machine may be used in combination with, or auxiliary to, other kinds of machines for operating on welt, or it may be used wholly independently of any other machine.

For the purpose of defining the novel features and advantages of the present invention, Goodyear welt will be referred to generally hereinafter, but those skilled in the art will recognize that the invention is not limited to tempering only this type of welt.

Welting of all kinds may come to the shoe manufacturer from the welt manufacturer in one of two forms according to the manufacturer's needs. The majority of shoe manufacturers desire that the welt be delivered to them in hanks while the remainder desire that it be wound on a spool. The present invention will handle equally well both hanked or reeled welt and will temper either perfectly without change in the devices which direct the welt through the water.

Prior to the present invention many attempts have been made to design a machine for wetting or moistening welt in a manner to insure that only the portion of the welt that is to receive the inseam stitches will be so tempered as to insure a tight inseam when presented to the stitch-forming mechanism of the inseam sewing machine. These have included a machine having provision for delivering water through a nozzle into the stitch-anchoring groove in the flesh side of the welt; another having provision for quickly drawing the welt on edge between side guides, rising above the water level, in a tank of water with its beveled edge immersed to at least the depth of the groove; and a third having provision for wetting only the flesh side of the welt. The aim and purpose of these various attempts at perfect-

the welt from being wet too much or too long by the water and particularly to prevent wetting the grain surface of the welt that is to be exposed on the shoe. Success has not crowned these inventions as none are in commercial use today and shoe manufacturers have, up to the introduction to them of the machine of this invention, been forced to continue to use the crudest and earliest known method of tempering welt, namely, dipping the entire blank in water and then waiting for it to dry out enough to insure sewing a tight inseam.

When the process of dipping the hank to temper the welt first came into use the leather used for welt was prepared in quite a different manner than it is today. The tanning processes were such that the hard leather needed, before sewing, to be soaked and then to dry and mull under cover until it became soft and cheesy thus insuring a tight inseam but, at the same time, developing many disadvantages. Today the leather for welt is curried before it is stripped into fillets and is, therefore, quite mellow after the cutting operation to produce the grooved and beveled strand. Such welt does not need to be soaked and then mulled. Its tannage is such that the only necessary treatment is a moistening of the inner margin that is to receive the inseam stitches. And yet, because no satisfactory process for merely moistening has heretofore been developed, the welt of today is treated prior to sewing just as it was when soaking was essential.

Many disadvantages flow from submersion of the hank in water. If soaked too long the welt, particularly narrow and thin women's welt, will stretch during the inseaming operation and the full width of the extension on the shoe is lost. This means "cripples", necessitates discarding the imperfect shoes, and adds expense both in material and time required to manufacture replacement shoes. Contact of the wet grain side with delicate upper leathers will stain them and this is necessarily concomitant when the hank submersion method of tempering is employed.

If the dipped welt is allowed to dry too

100

much it becomes brittle and weak in the fibre, particularly on the grain side, which interferes with the inseaming and welt beating operations and promotes cripples. Unless a hank, tempered by submersion, is entirely used at the end of a day's stint then the unused remainder may become so hard and brittle by the next day that it requires re-tempering with the attendant disadvantages. Welting today is made from high grade leather which is so tanned that it is meant to be wet only once and then harden, where water has been applied, while on the shoe. A second all over wetting will cause it to shrink in width and become harder. Aside from a loss of shape, which is particularly disadvantageous because manufacturers watch the width of welting (extension on the shoe) down to $\frac{1}{2}$ of an inch and further, the hard welt is more difficult to sew and operate on later. Welting leather is always stretched before cutting into fillets and it is the later shrinking after tempering which hardens it and tightens the inseam.

From the foregoing it is obvious that welt tempering is a delicate and highly important operation the main requirement of which has always been, but not attained up to the time of this invention, to wet or temper only just enough of the inner margin of the welting to enable the inseam sewing machine to sew a tight seam, and at the same time be sure that no water seeps over, or in any way is drawn toward or impinges upon, the grain surface that is to be exposed on the shoe. Thus all the disadvantages hereinbefore recited are wholly eliminated. A further advantage of correct welt tempering comes from the ability to immediately sew and beat out the sewed welt, whereas with welting tempered by submersion there must be a drying period of several hours between successive operations.

The object of the present invention is to provide a process of tempering welting, and a machine for carrying out the process, that will invariably wet or moisten only that much of the grooved margin of the welting as is required for sewing a tight inseam, and no more. The various novel features of the machine through which this is made certain will be ascertained from the following description.

To the accomplishment of this object and such others as may hereinafter appear, as will readily be understood by those skilled in the art, the invention comprises the features and combinations of parts hereinafter described and then particularly pointed out in the appended claims.

The features and scope of the invention will best be understood from a description of the preferred embodiments thereof illustrated in the accompanying drawings, in which:

Figure 1 is a view, in rear elevation, of the

preferred form of welt carrier for directing the wetting through the wetting tank;

Fig. 2 is a view, in front elevation, of the carrier shown in Fig. 1, detached from its support;

Fig. 3 is a view, in right side elevation and partly in section, of the tank, welt carrier and device for removing kinks from the hank;

Fig. 4 is a view, in front elevation, of the kink removing device;

Fig. 5 is a view, in plan, of the entire machine with its base plate shown clamped to the work table (dotted lines) of an inseam sewing machine. In this figure the circular dotted line represents the column of an inseam sewing machine such, for example, as is disclosed in Letters Patent of the United States to Andrew Eppler No. 1,076,878, dated October 28, 1913;

Fig. 6 is a view, in rear elevation, of the means at the forward end of the tank for directing the strand to the welt carrier;

Fig. 7 is a view, in front elevation, of a modified form of welt carrier;

Fig. 8 is a view, in front elevation, of the carrier shown in Fig. 7, detached from its support;

Fig. 9 is a view, in right side elevation, of the entire machine fitted with the modified form of welt carrier; and

Fig. 10 is a view, in longitudinal section, of the tank with welting being directed therethrough by the modified welt carrier.

In the embodiment of the invention illustrated by Figs. 1, 2, 3 and 5 of the drawings I show what I term a "universal" welt carrier indicated generally by 10, so constructed as to be adjustable to receive many different sizes of welting within certain limits. The guide 10 is suspended above a water tank 12 from a cross-bracket 14 which is adjustable vertically on guide pins 13 and 15 secured at each side of the tank 12.

The water in the tank 12 is maintained at a constant level by means of an intermittent feed, from the supply contained in a bottle or other container 16 (see Fig. 9), induced by evaporation from the tank under the well-known barometric principle. The contents of the bottle is sealed to the atmosphere, by reason of its air-tight support in the bottle holding mouth 17 (Figs. 5 and 9), and evacuation to the tank 12 can occur only when the water level in the tank is lowered sufficiently to uncover the upper end of a water gate 18. This water gate has an inverted V shape (as indicated by dotted lines Fig. 5) so that the replenishing is in such small quantities as not to disturb the calm of the water in the tank 12.

The adjustable guide bracket 13 provides for setting the welt guide 10 to a predetermined depth in the water of the tank; to accommodate any size or style of welting held by the carrier, i. e. in order to obtain the same

proportional wetting of the width of the welting regardless of size. To accomplish this the guide bracket is provided at its ends with a sleeve 20 and a fork 22 the latter of which engages the guide pin 15. The upper 5 end of the pin 13 carries a collar 24 held in any vertical position thereon by a set screw 25 (Fig. 5). Depending from the collar 24 is a tubular extension 23 preferably integral 10 with the collar and in any event adjustable vertically on the pin 13 with the collar. This tube 23 forms a slide bearing for the bracket sleeve 20. A crank arm 26, having a handle 28, is pivotally mounted on the collar and a 15 vertical, pivoted link 30 connects the sleeve 20 to the crank arm. The crank arm and link form a toggle with its knuckle at 29 and a stop pin 31 on the collar serves to maintain the toggle straight when the handle 28 is 20 moved to the left, as shown by Fig. 1. When the toggle is straight, or extended, the welt carrier support 14 is at its lowest position determined by the setting of the collar 24. By 25 loosening the set screw 25 the support 14 and its depending welt carrier 10 may be moved together, due to the toggle connection, toward or from the water level until the desired setting is attained. It may be desirable, at times, to wholly remove the carrier and support 30 from the pins 13 and 15. In order to preserve the setting attained by the previous adjustment, and eliminate re-adjustment when the parts are replaced, the lower end of the pin 13 may be threaded and provided with a 35 nut 32 (Fig. 1) to be screwed against the lower end of the tube 23 after an adjustment has been perfected and then held in position by a lock-nut 33 or other suitable securing means. The nut 32 thus functions as a fixed 40 stop to determine the vertical position of the welt carrier with respect to the water level.

The universal welt carrier 10 has three parts; a body member 34 having extending pins 36 and 38 set at right angles to each other, a side-guide member 40 slidable on the pin 36, and an end-guide member 42 slidable on the pin 38. The adjustable members 40 and 42 are held at any desired position on their pins by set screws 41 and 43 respectively. The 45 side-guide member 40 is constrained to move longitudinally, without rotation, on its pin 36 by a face bearing 44 between it and the body member. The end-guide member 42 is constrained to move on its pin 38 in a like 50 manner by a slide bearing comprised of a fork 45 which embraces the reduced end of a lateral leg 46 of the side-guide member. The forked bearing serves to maintain the end and side members in the same plane under 55 all conditions of adjustment and the face bearing co-operates therewith to maintain the end and side members in the plane of the body member. It is obvious from a study of Figs. 1 and 2 how the size of the opening, or 60 guide eye formed by the three members of the

welt carrier may be altered to accurately engage and direct through the water tank different widths or thicknesses of welting.

It is of the utmost importance that the 70 welting drawn through the welt carrier, and thus through the water, be so held that only its grooved margin will be moistened. Insurance must be had that the portion of the grain which is to be exposed on the shoe is 75 protected from immersion. To this end provision is made for setting the welt carrier in such a position that the welting, while in the guide eye, stands oblique to the water level with its grain side uppermost and its 80 grooved margin tipped downward for immersion as the welting is drawn across the tank 12. This angular adjustment of the welt carrier is secured by making a head 48 on the body member 34 slidable in a curved way 50 (see Fig. 3) formed on the carrier support 14. 85 The carrier 10 is held in any desired position along its support 14 by a lock screw 49.

I will now describe a feature of my welt carrier that I deem to be essential in that it 90 functions to maintain the grain surface to be exposed on the shoe perfectly dry throughout the tempering operation. It will be observed (Figs. 1 and 2) that the lower end of the body member 34 of the carrier is cut away at 95 52, preferably but not necessarily, a semi-circular cavity, the lower corner 54 of which bears on the welting either directly at, or if desired just beyond, the grain corner formed by cutting the welt bevel, or opposite the groove in the flesh side. The arc of the 100 curved way 50 is struck from this corner 54 as a center and all angular movement of the welting relative to the water level takes place about this fixed center of adjustment. The preliminary vertical adjustment of the welt carrier 10 is such that the corner 54 stands at, or possibly just above, the water level, 105 hence no matter how much the angle is decreased between the flesh side of the welting and water level, in order to wet more of the flesh side, the grain side of the welting will 110 never be immersed beyond the line of pressure of the corner 54. Furthermore the cavity 52 provides a shoulder rising from the grain functioning to prevent water being 115 drawn by capillary attraction beneath the grain side wall of the guide-eye and thence on to that portion of the grain to be exposed on the shoe. Moisture will not seep upward beyond the corner 54 but it will do so if the 120 grain side wall of the guide eye is made as a continuous surface similar to the flesh side wall formed by the leg 46. The flesh side wall of the guide eye may be provided with a cavity to overcome capillary seepage of the 125 moisture (it is so shown in Fig. 8) but a wetting of even the whole of the flesh side of the welting is not disadvantageous. It will be observed that the side and end-guide members 130 40 and 42 both move on the body member to-

ward and from the fixed point 54 on that member thus preserving the grain side depth of immersion for all sizes of welting for which the carrier may be adjusted.

5 The machine is set at a convenient height upon a bench or table and the welting to be tempered comes from a hank or reel at a lower level, passing upward over a directing bar 56 (Fig. 6), having an upper protecting pin 58, on the forward edge of the tank 12. The surface of the bar 56 slants relatively to the water level, the obliquity approximating that of the guide eye of the welt carrier 10, to relieve strain on the guide eye. As best 15 shown by Fig. 2 the ends of the guide eye may be provided with rounded abutments 59 to further assist the welting in an easy passage through the welt carrier. After immersion the welting passes beneath a guide roll 60 which is freely rotatable on a pin 61 held at each end in brackets 62 (Fig. 5) that are angularly adjustable in ears on the tank walls to enable the guide roll to be set in the best 20 position for lifting the welting out of the water immediately it has passed beyond the welt carrier. From the roll 60 the moistened welting passes upward (see Fig. 3) conveniently to the measuring roller 64 of the inseam sewing machine. This roller is provided 25 with clamping mechanism for holding the welting after the welt cutting operation is performed on completing the sewing of a shoe.

30 The general location of the roller 64 is indicated by dotted lines in Fig. 5 and this figure shows also how the machine of the present invention may be mounted on a rear corner of the sewing machine work table. The work table 65 has a bounding lip or rib 66 from which is hung a base plate 68 for supporting the tempering machine. The base plate has two holes 69 at one end which, when the plate is situated diagonally beneath the table 65 (see Fig. 5), are just outside the rib 66 and this end of the base plate may thus be clamped to the table by U-bolts 70 which pass upward and hook over the rib. The other end of the base plate is provided with two spaced posts 72 (see also Fig. 9) having reduced ends forming shoulders on which rest collars 73 at the ends of arms 74 extending laterally from the tank 12. The machine is removable at will from the posts 72 for dismantling, inspection or repair.

55 From the measuring roller 64 the welting goes to the welt guide of the sewing machine and from thence to the work-feeding and stitch-forming mechanisms. Between the two rolls 60 and 64 the welting is turned over 60 so as to lie flesh side up, as it passes to the sewing machine welt guide, in proper position to be stitched to the shoe. This twist in the welting does not interfere with the 65 advance of the tempered welting by the work-feeding mechanism because there is about a

yard of moistened welting between these two rolls; and this length is amply sufficient to give the welting a long enough period between moistening and sewing to permit a substantial penetration of the moisture and provide a tempered condition of the inner margin that is perfect for piercing by the awl and needle and the formation of a tight inseam. When the welting is cut, after completing the operation on a shoe, the operation 75 of the clamp on the roller 64 holds taut the length of welting between the measuring roller and the roll 60 and prevents the portion between the roll 60 and the welt carrier 10 (see Fig. 3) from dropping downward 80 into the water. If there is any slack the weight of the substantially vertical run will cause it to sag downward outside the tank and thus straighten the portion inside the tank and hold it above the water level. 85

At night, after the day's work is over, it is not necessary to unthread the welting still unused from the guide eye of the carrier 10. By moving the handle 28 (Fig. 1) to the right the toggle 26—30 is broken and the support 14 with its welt carrier is lifted on the tube 23 to a position where the welting is above the water level. A contractile spring 75 connected to pins on the sleeve 20 and fixed collar 24 prevents the guide 10 from sliding down again due to its own weight. In consequence the unused welting, not being left overnight in a soaked condition as was the practice prior to this invention, is in prime condition for tempering and stitching when the sewing machine operator starts the next morning. 95

In the modified form of the invention shown in Figs. 7, 8 and 9 the tank 12 and its water supply and support, the forward bar 56 and the rear roll 60, and in general the adjusting mechanism for setting the welt carrier as a whole for correct immersion of the grooved margin of the welting, are all unchanged. In Fig. 7 the dot and dash lines 100 show the raised position of the welt carrier after the handle 28 has been moved and the toggle 26—30 broken as has hereinbefore been described. 105

110 The construction of the welt carrier constitutes the principal modifications. The modified welt carrier comprises a disk 80 having a plurality of guide eyes of different sizes for accommodating different sizes of welting. This disk 80 is mounted in a split-ring portion 82 depending from the welt carrier cross-bracket 84. The disk has a flanged forward edge (see Fig. 10) and after seating in a complementary recess in the split-ring is held therein by a clamping screw 85. Each guide eye is characterized by the recessed or broken grain side wall, as described for the guide eye of the preferred form. Each cavity 86 in the grain side wall has the same abrupt grain side engaging cor- 115

5   ner 54, as hereinbefore described, to prevent wetting of the grain by capillary attraction between the wall and welting, and any one of these several guide eyes, when in 10   operative position as shown by Fig. 7, serves the same end as does the adjustable guide-eye of the preferred form. Each 15   guide-eye opens through the peripheral edge of the disk 80 thus permitting the disk to be applied to welting already threaded through 20   the machine (see Fig. 8). There may be heavy places in the hank and while the fit should be close yet the welting should travel 25   freely through the welt carrier.

15   In Figs. 3 and 4 there is shown a device, applicable to either form of the invention, for taking all kinks out of the welting before passing over the directing bar 56. Kinks are very apt to form in welting drawn from 20   a hank and this is one advantage of using reeled welting. A bracket 90 projects forwardly from the front wall of the tank and carries a loosely rotatable directing roll 92, set slightly oblique to the horizontal in con- 25   formance with the obliquity of the directing bar 56. Depending from the bracket 90 are two bars 94 having inwardly turned ends (Fig. 4) about which is clamped a mouth formed of two pieces 96 of generally triangular form, the pointed ends being directed 30   downward toward the hank of welting. The mouth pieces constitute a guide for the welt and have smooth opposed faces spaced apart 35   a distance to accommodate the thickest welting that may be used. The pointed ends are rounded, forming together a nose about which a guard in the form of a ring 98 is soldered. If the welting becomes twisted (see Fig. 3) 40   passage through the guide formed by the two pieces 96 will cause it to untwist. This untwisting may develop a kink (see Fig. 4) in which event the edge of the kinked welting rides against the under surface of the 45   guard 98 and eventually is thrown back after the twisted portion has been fed through. A device of this nature is quite necessary in feeding to the machine from hanks.

50   In setting up the machine it may be found that the bench, or other support, is not level in which event the water level will not be parallel to the upper plane of the tank as 55   illustrated by Figs. 1 and 9, showing the ideal condition. Under such conditions the welt carrier is first adjusted both vertically and angularly, as hereinbefore described, to as 60   perfect a position as possible and then the water level is changed, is found necessary to prevent wetting more than the grooved margin of the welting, by the water level adjustment shown in Fig. 9. The mouth 65   17 for receiving the bottle neck is provided with a vertically adjustable bottle neck holder 100 held in any desired position by set screws or other suitable securing means. By 120   altering the vertical location of the mouth

of the bottle 16 by an adjustment of the collar 100 such a variation of the water level in the tank 12 may be attained as to properly supplement the welt carrier adjustment and insure a passage of the strand across the 125   tank without wetting its grain surface to be exposed on the shoe.

In the foregoing description and in the appended claims the term "water" is used as inclusive of any welt moistening fluid that may be, or is capable of being, used for tempering shoe welting.

Many modifications and changes in detail will readily occur to those skilled in the art without departing from the spirit and scope of my invention, but having set forth the objects and nature of my invention, and having shown and described constructions embodying the principles thereof, what I claim as new and useful and of my own invention, and desire to secure by Letters Patent is:—

1. A machine for tempering shoe welting having, in combination, a tank adapted to hold water, means for directing a strand of welting across said tank, means for causing said strand to be only partially immersed during its passage across the tank, and means under the control of the operator acting when actuated to raise the immersed portion above the water level at the will of the operator.

2. A machine for tempering shoe welting having, in combination, a tank adapted to hold water, and means within the tank for directing a strand of welting through the tank with a margin only thereof immersed, said means being adjustable relative to the water level to vary the extent of said immersion.

3. A machine for tempering shoe welting having, in combination, a tank adapted to hold water, means for directing a strand of welting through the tank, means for causing said strand to be only partially immersed during its passage across the tank, and means under the control of the operator acting when actuated to withdraw said welting from the water and return it to the same position with relation to the water level.

4. A machine for tempering shoe welting having, in combination, a tank adapted to hold water, means for controlling the degree of immersion of welting passing through the tank removable at will from the machine, and adjustable means for preserving the setting to permit replacement with the original setting.

5. In a machine for tempering shoe welting of the type having a tank adapted to hold water for immersion of a margin of the welting, a welt carrier having means for holding and directing a strand of welting through the tank, and means for setting the carrier in a position to maintain the strand during its immersion with its side faces in a predetermined position of obliquity transversely of

the welting relative to the water level with its grain side uppermost and with its grooved margin only immersed.

6. In a machine for tempering shoe welting of the type having a tank adapted to hold water for immersion of a margin of the welting, a welt carrier having adjustable means for holding and directing a strand of welting through the tank, and means for adjusting the carrier to support the strand with its inner margin immersed and its grain side above the water level regardless of the size of the welting in the carrier.

7. In a machine for tempering shoe welting of the type having a tank adapted to hold water for immersion of a margin of the welting, a welt carrier having means for holding and directing a strand of welting through the tank and adjustable to receive different sizes of welting, and means for adjusting said carrier angularly with relation to the water level about an axis parallel to the line of travel, said adjustment being invariably about the same center regardless of the size of the welting in the carrier.

8. In a machine for tempering shoe welting of the type having a tank adapted to hold water for immersion of a margin of the welting, a welt carrier having a wall at both the grain and the flesh sides of the strand carried thereby for holding and directing said strand through the tank, and means for adjusting the carrier angularly with relation to the water level about an axis lying in the plane of the wall at the grain side.

9. In a machine for tempering shoe welting of the type having a tank adapted to hold water for immersion of a margin of the welting, a welt carrier having a wall at both the grain and the flesh sides of the strand carried thereby for holding and directing said strand through the tank, means for adjusting the flesh side wall to accommodate different thicknesses of welting, and means for adjusting the carrier angularly about an axis invariably defined substantially by the grain corner of the welting regardless of its thickness.

10. In a machine for tempering shoe welting, a welt carrier comprising a fixed body member having pins extending longitudinally and laterally thereof, and end and side members slideable respectively lengthwise of said pins and shaped to form between them and said body member a guide eye through which the strand passes.

11. In a machine for tempering shoe welting, a welt carrier comprising a fixed body member having pins extending longitudinally and laterally thereof, end and side members slideable respectively lengthwise of said pins and shaped to form between them and said body member a guide eye through which the strand passes, and means to prevent angular

movement on its pin of either slideable member.

12. In a machine for tempering shoe welting, a welt carrier comprising a fixed body member having pins extending longitudinally and laterally thereof, end and side members slideable respectively lengthwise of said pins and shaped to form between them and said body member a guide eye through which the strand passes, and a slideable connection between said end and side members adapted to maintain them both in the same plane under all conditions of adjustment. 70

13. In a machine for tempering shoe welting, a welt carrier comprising a fixed body member having pins extending longitudinally and laterally thereof, end and side members slideable respectively lengthwise of said pins and shaped to form between them and said body member a guide eye through which the strand passes, and means for maintaining said end and side members in the plane of said body member under all conditions of adjustment. 80

14. In a machine for tempering shoe welting, a tank adapted to hold water, and means for directing a strand of welting across said tank comprising, a welt carrier having a guide eye for directing the strand through the carrier arranged to cause the inner margin only of the strand to be immersed during its passage across the tank, said guide eye having continuous walls adapted to engage the ends and flesh side of the welting, and a two part wall adapted to engage the grain side of the welting said parts being separated by an opening between them, and the inner corner of the part nearest the inner margin of the strand having a bearing thereon at substantially the water level on the line defined by the joinder of the bevel with the grain. 90

15. In a machine for tempering shoe welting a tank adapted to hold water, and means for directing a strand of welting across said tank comprising, a welt carrier having a guide eye having four walls adapted to engage the ends and sides of the strand being directed thereby through the carrier and arranged to cause the inner margin only of the strand to be immersed during its passage across the tank, the wall adapted to engage the grain side of the welting having a shoulder rising abruptly from said grain side at substantially the water level at substantially the edge of the welt bevel on that side. 110

16. A machine for tempering shoe welting having, in combination, a tank adapted to hold water, a vertical guide pin at each side of said tank, a cross support having a dependent welt carrier slideable on said pins toward and from a position in which the welt is only partially immersed, and means under control of the operator for moving said support on its pins and holding said 120

carrier in either its upper or lower position.

17. A machine for tempering shoe welting having, in combination, a tank adapted to hold water, a vertical guide pin at each side of said tank, a cross support having a dependent welt carrier slidable on said pins toward and from said tank, a collar fixed to one of said pins, toggle links connecting said collar and support, and a handle connected to one link for making and breaking said toggle.

18. A machine for tempering shoe welting having, in combination, a tank adapted to hold water, a vertical guide pin at each side of said tank, a cross support having a dependent welt carrier slidable on said pins toward and from said tank, a collar fixed to one of said pins, toggle links connecting said collar and support, a handle connected to one link for making and breaking said toggle, and a contractile spring connecting said collar and support.

19. A machine for tempering shoe welting having, in combination, a tank adapted to hold water, a welt carrier positioned within the tank to permit immersion of a strand of welting held thereby, and means for adjusting said carrier to change the vertical position and transverse inclination of the welt strand with relation to the water level.

20. A machine for tempering shoe welting having, in combination, a tank adapted to hold water, means for directing a strand of welting across the tank and into contact with the water, and means for removing kinks from the welting prior to its contact with the water comprising a guide for the welting and a guard to engage and throw back a kink in the welting.

21. A machine for tempering shoe welting having, in combination, a tank adapted to hold water, means for directing a strand of welting across the tank and into contact with the water, a guide for the welting at the forward end of the tank a guard cooperating therewith to uncurl and straighten the welting being directed across the tank.

22. A machine for tempering shoe welting having, in combination, a tank adapted to hold water, means for directing a strand of welting across the tank above the water level, a welt carrier for deflecting the strand into the water during its passage across the tank, and a device for de-kinking the welting before being acted upon by said welt carrier comprising a guide for the welting and a guard to engage and throw back a kink in the welting.

23. A machine for tempering shoe welting having, in combination, a tank adapted to hold water, means for directing a strand of welting across the tank, and a welt carrier provided with a guide eye through which the welt may be freely drawn arranged to maintain the welting during its passage through

the water with its side faces inclined to the water level transversely of the welting with its grain side uppermost and with its grooved margin only immersed.

24. A machine for tempering shoe welting having, in combination, a tank adapted to hold water, means for directing a strand of welting across the tank, a welt carrier provided with a guide eye through which the welt is drawn located at the lowest point in the travel of the welt to change the lead of the welt abruptly from a downward to an upward direction, and to maintain the welt during its passage through the water with its side faces inclined to the water level transversely of the welting with its grain side uppermost and with its grooved margin only immersed.

25. A machine for tempering shoe welting having, in combination, a tank adapted to hold water, means for directing a strand of welting across the tank, and a welt carrier provided with a guide eye through which the welt is drawn having the greatest of its three dimensions widthwise of the welt and being arranged to maintain the welting during its passage through the water with its side faces inclined to the water level transversely of the welting with its grain side uppermost and with its grooved margin only immersed.

26. A machine for tempering shoe welting having, in combination, a tank adapted to hold water, and means for causing the strand of welting to pass across the tank and through the water and for maintaining the welt during its passage through the water with its margin only immersed and with its side faces inclined to the water level.

27. A machine for tempering shoe welting having, in combination, a tank adapted to hold water, and means for causing a strand of welting to pass across the tank and through the water and for maintaining the welting during its passage through the water with its side faces inclined to the water level transversely of the welting with its grain side uppermost and with its grooved margin only immersed.

28. A machine for tempering shoe welting having, in combination, a tank adapted to hold water, means for directing a strand of welting across said tank, and a welt carrier having a guide eye through which the strand passes, arranged to cause the strand to be only partially immersed during its passage across the tank and to hold the strand with its flesh side down and inclined to the water level, said guide eye having an adjustable end wall engaging the outer margin of the strand and an adjustable side wall engaging the fresh side of the strand for accommodating welting of varying widths and thicknesses.

29. A machine for tempering shoe welting having, in combination, a tank adapted to hold water, means for directing a strand of welting across said tank, and a welt carrier

having a guide eye through which the strand passes arranged to cause the strand to be only partially immersed during its passage across the tank, said guide eye having a wall, 5 a portion of which engages the grain side at the inner margin of the welt below the water level and terminates in a shoulder substantially at the water level opposite that portion of the grain surface which is concealed in the 10 finished shoe.

30. A machine for tempering shoe welting having, in combination, a tank adapted to hold water, means for directing a strand of welting across said tank, and a welt carrier 15 having a guide eye through which the strand passes arranged to cause the strand to be only partially immersed during its passage across the tank, said guide eye having a two-part wall engaging the grain side of the strand at 20 the inner and outer margins of the strand, the part at the inner margin engaging the welt below the water level and terminating substantially at the water level in a shoulder along a line substantially opposite the groove 25 in the flesh side of the welt.
